FLOOR MACHINES

Frank J. Pollnow, Jr., Ladue, Mo., assignor to Vestal Laboratories, Inc., St. Louis, Mo., a corporation of Missouri

Filed May 21, 1959, Ser. No. 814,834
5 Claims. (Cl. 15—246)

This invention relates in general to certain new and useful improvements in floor machines and, more particularly, to a splash collar for floor machines.

Most floor machines which are in use today comprise an electric motor mounted vertically upon a flat somewhat circular hollow base having a large disk-shaped brush or applicator which is rotated by the motor. A long handle extends angularly upwardly to facilitate guiding and directing the machine to and fro over the area to be treated. For example, where a floor is to be scrubbed, the floor scrubbing operation is carried out by thoroughly wetting the floor with water and soap or detergent and moving the scrubbing machine over the floor surface. The rotation of the brush, however, tends to sling the dirty soapy water outwardly with considerable centrifugal force around the entire periphery of the machine. In the middle of the floor area being scrubbed, this is only a minor inconvenience, but adjacent to walls, columns, furniture, and the like the outwardly slung water splashes up and soils such upright surfaces and presents a serious problem. In fact, at the present time, many custodial employees do not run the scrubbing machine close to walls, preferring instead to rely on hand mopping in the hope the floor is not quite so heavily soiled near the wall and will, therefore, be adequately cleansed without scrubbing. Similarly, stains, sealing preparations, and finishes can be applied to a floor by a floor machine equipped with a suitable applicator, but the problem of splashing the applied material is substantially the same as with scrubbing operations.

It is, therefore, the primary object of the present invention to provide a splash guard for floor machines of the rotary brush or applicator type which will prevent wall splashing as the floor machine is used adjacent to walls and similar vertical surfaces.

It is another object of the present invention to provide a splash guard of the type stated which is simple and economical in cost and construction.

It is a further object of the present invention to provide a splash guard of the type stated which can be easily and quickly installed upon a floor machine and will readily adjust its vertical position as the floor machine is moved about to ride over uneven spots in the floor and conform to various positions of the floor machine itself.

With the above and other objects in view, my invention resides in the novel features of form, construction, arrangement, and combination of parts presently described and pointed out in the claims.

In the accompanying drawings—

FIG. 1 is a perspective view of a splash guard constructed in accordance with and embodying the present invention;

FIG. 2 is a side elevational view of the splash guard shown in FIG. 1;

FIG. 3 is a perspective view of a floor machine with the splash guard in place thereon;

FIG. 4 is a vertical elevational view of the floor machine with the splash guard shown in section to illustrate the operative position of the splash guard in relation to the floor machine when the latter is in actual use;

FIG. 5 is a perspective view of a modified form of splash guard constructed in accordance with and embodying the present invention;

2

FIG. 6 is a vertical elevational view of another type of floor machine for which the splash guard shown in FIG. 5 is particularly adapted, the splash guard being shown in section in order to illustrate the operative position of the splash guard in relation to such floor machine;

FIG. 7 is a fragmentary end elevational view of the splash guard shown in FIG. 5, illustrating in more detail the fastening means used in conjunction therewith;

FIG. 8 is a fragmentary sectional view taken along line 8—8 of FIG. 7;

FIG. 9 is a perspective view of another modified form of splash guard constructed in accordance with and embodying the present invention;

FIG. 10 is a perspective view of still another type of floor machine for which the splash guard shown in FIG. 9 is particularly adapted;

FIG. 11 is a perspective view of another modified form of splash guard constructed in accordance with and embodying the present invention;

FIG. 12 is a side elevational view of the splash guard shown in FIG. 11;

FIG. 13 is a perspective view of a floor machine with the splash guard of FIG. 11 in place thereon; and

FIG. 14 is a vertical elevational view of the floor machine with the splash guard of FIG. 11 shown in section thereon.

Referring now in more detail and by reference characters to the drawings, which illustrate practical embodiments of the present invention, A designates a splash guard comprising a continuous annular collar-like member 1, which is formed preferably of a polymerized synthetic resin, such as molded polystyrene or other suitable material which is hard enough to wear well against abrasion, but which will not mark or mar the floor. Around its upper margin, the collar-like member 1 is formed inwardly to a somewhat reduced diameter in the provision of a somewhat frusto-conical flange 2, and around its lower margin the member 1 is notched to provide a uniformly spaced annular series of tines 3, the points of which all lie in a flat plane so as to rest flush upon the floor when the splash guard A is in operative position upon a floor machine M, as shown in FIG. 3. It should be noted that the inside diametral size of the splash guard A is slightly greater than the largest diametral size of the floor machine M so as to fit freely and loosely thereabout. Furthermore, the vertical height of the splash guard A is such that the flange 2 will fit loosely around and over the peripheral margin 4 of the machine-base 5, as shown in FIG. 4. When in use, the splash guard moves back and forth over the floor with the floor machine M and rides in a so-called "free-floating" manner so that the floor machine can be swung around or tilted at will. The tips of the tines 3 ride lightly over the floor F and effectively intercept all splash without interfering in the least with the scrubbing action of the machine M. Since the splash guard is fabricated from a suitable synthetic resin, it is not affected by the chemical action, if any, of the soaps or cleansing solutions used in floor scrubbing operations and the tines 3 will not mark or mar the floor surfaces.

The splash guard A is of a size and shape for fitting around a floor machine of brush-supported type, such as the floor machine M. However, many floor machines in use are of the transport wheel type, such as the floor machine M' shown in FIG. 6. For such type of scrubbing machine, it is preferable to employ a splash guard A', as shown in FIG. 5, which is substantially similar to the previously described splash guard A except that it comprises a collar-like member 6 which is split at the rear, as at 7, and provided with overlapping tabs 8, 9, releasably secured together with conventional snap-fas-

tener elements 10, 11, respectively. Beneath the tabs 8, 9, the collar-like member is cut away to provide a clearance notch 12 adapted to fit loosely around the transport wheels *w* of the scrubbing machine *M'*.

Another type of floor machine which is commonly in use is the so-called "heavy-duty" type, such as the machine *M''* shown in FIG. 10 and having a rearwardly extending housing *h* which covers an auxiliary wheel assembly *x*. For such type of scrubbing machine, it is preferable to provide a modified form of splash guard 10 comprising a unitary collar-like member 13 which is substantially similar to the previously described splash guard A except that it includes an integrally molded rear projection 14 having a flat top 15 shaped to fit over and around the housing *h*. The wall 15 is dimensioned for somewhat loose-fitting disposition around the floor machine *M''* so as to achieve the same "free-floating" action as the previously described embodiments.

It is also possible to provide a modified form of splash guard A'', as shown in FIGS. 11 to 14, inclusive. This splash guard A'' is similar in construction to the previously described splash guard A, including a continuous annular collar-member 1' molded or otherwise suitably formed around its upper margin in the provision of a somewhat frusto-conical flange 2'. Around its bottom or floor-contacting margin, the splash guard A'' is straight and the tines 3 of splash guard A are omitted, so that the entire edge rests substantially upon the floor. Splash guards A'' are particularly useful in conjunction with applicator type machines, that is to say, machines for applying color pastes. It can be mounted on the floor machine R, as shown in FIGS. 13 and 14.

It should be understood that changes and modifications in the form, construction, arrangement, and combination of the several parts of the floor machines may be made and substituted for those herein shown and described without departing from the nature and principle of my invention.

Having thus described my invention, what I claim and desire to secure by Letters Patent is:

1. A splash guard for use with a floor machine including a rotating means operatively mounted beneath an annular shell which is provided with a diametrically enlarged annular rim, said splash guard comprising an annular skirt sized for loose-fitting disposition over the shell and including an integral diametrically reduced frusto-conical flange sized for loose-fitting contact with the rim, said skirt being sized in height for normal floor-wise contact when the flange is in substantial contact with the rim, whereby said splash guard will be slidably mounted on said annular shell in a free-floating manner, the lower margin of the skirt being provided with a plurality of

tines for reducing the frictional contact between the skirt and the floor.

2. A splash guard for use with a floor machine including a rotating means operatively mounted beneath an annular shell which is provided with a diametrically enlarged annular rim, said splash guard comprising an annular skirt sized for loose-fitting disposition over the shell and including an integral diametrically reduced frusto-conical flange sized for loose-fitting contact with the rim, said skirt being sized in height for normal floor-wise contact when the flange is in substantial contact with the rim, whereby said splash guard will be slightly mounted on said annular shell in a free-floating manner, the lower margin of the skirt being provided with a plurality of uniformly spaced tines for reducing the frictional contact between the skirt and the floor.

3. A splash guard for use with a floor machine including a rotating means operatively mounted beneath an annular shell which is provided with a diametrically enlarged annular rim and also includes a floor-contacting roller mounted adjacent said shell, said splash guard comprising an annular skirt sized for loose-fitting disposition over the shell and including an integral diametrically reduced portion adapted for loose-fitting engagement with the shell, an integral diametrically reduced frusto-conical flange sized for loose-fitting contact with the rim, and means for covering said roller and thereby preventing any splash from escaping from the machine in the direction of said roller, said means being integrally connected to the skirt and also being loosely disposed over said shell, said skirt being sized in height for normal floor-wise contact when the diametrically reduced portion and flange are respectively in substantial contact with the shell and the rim, whereby said splash guard will be slidably mounted on said annular shell in a free-floating manner.

4. The device of claim 3 wherein the covering means comprises a housing integrally formed with the skirt and including an upper covering member, the inner margin of which is a smooth continued extension of the upper margin of the skirt.

5. The device of claim 3 wherein the entire device is composed of a single piece of synthetic resin material.
